UNITED STATES PATENT OFFICE.

MARIUS E. GRISWOLD, OF BURLINGTON, IOWA.

AUTOMATIC STOP FOR PHONOGRAHS.

Application filed February 7, 1921. Serial No. 442,926.

To all whom it may concern:

Be it known that I, MARIUS E. GRISWOLD, a citizen of the United States, residing at Burlington, in the county of Des Moines and 5 State of Iowa, have invented certain new and useful Improvements in Automatic Stops for Phonographs, of which the following is a specification.

This invention relates to an automatic 10 stop for phonographs and has for its primary object to provide a simple and efficient device for automatically stopping the turn-table of the phonograph at the completion of a predetermined advance of the stylus 15 in the record groove.

Another important object of the invention is to provide an automatic stop mechanism which is actuated by the rotation of the turn-table.

20 Further objects of the invention are to provide manually operable auxiliary controlling means for the stop mechanism permitting the turn-table to be stopped at any time irrespective of the setting of the automatic stop, to provide clutch mechanism for controlling the actuation of the automatic stop, and to permit the entire stop mechanism to be located beneath the turn-table.

25 The many other objects and advantages 30 of the invention will be better understood by reference to the following specification when considered in connection with the accompanying drawing illustrating a selected embodiment thereof, in which:

35 Fig. 1 is a plan view of the invention with the latch released and the turn-table stopped.

Fig. 2 is the same as Fig. 1 but with the latch engaged and the turn-table released.

40 Fig. 3 is a section on the line 3—3 of Fig. 1; and

Figs. 4 and 5 are detail views.

Referring to the drawing, the automatic stop forming the present invention is mounted upon a base plate 10 which is secured 45 upon the usual top platform or motor board of the phonograph by screws 11 or other suitable means. This plate 10 is provided with an indicating dial 12 which is graduated to indicate the various settings of the 50 indicating pointer 13. The pointer 13 is pivotally mounted upon the plate 10 at 14 and is provided with a laterally projecting arm 15 extending substantially radially from the axis of revolution of the pointer. A

55 pin 16 has its lower extremity seated in

the outer end portion of the arm 15, and this pin projects through an arcuate slot 17 in the latch lever 18 and a longitudinal slot 19 in the trip 20. The latch lever 18 is pivotally mounted at 14 in the same manner as 60 the indicating arm 13. The trip 20 is pivotally mounted at 21 on the outer extremity of the latch lever 18.

A brake lever 22 is pivotally mounted at 23 upon the base plate 10. A brake 24 is 65 pivotally mounted at 25 on the outer extremity of the laterally projecting arm 26 formed on the brake lever 22. A clutch guide bar 27 has its extremities supported by oppositely disposed upturned lugs 28 and 70

29 formed respectively on the brake lever 22 and the clutch lever 22'. A clutch member 30 is slidably mounted upon this bar 27, and a coil compression spring 31 acts between this member 30 and the lug 28 to normally retain the clutch member against the lug 29. A friction washer 32 may be placed upon the bar 27 in contact with the inner 75

face of the lug 29 to eliminate any noise which might occur by the impact of the metal clutch member 30 with the lug 29 during the 80 operation of the stop mechanism. The outer portion of the clutch member 30 is provided with an elongated slot 33 through

which passes the feed screw 34. The outer 85 extremity 35 of the clutch member 30 has the form of a segment of a sleeve, and the inner face of this segment is threaded to mesh with the threads upon the feed screw 34 when moved into engagement therewith. 90

The outer extremity of the brake lever 22 is connected by an extensible spring 36 with a projection 37 on the latch lever 18. The latch lever 18 is provided with a shoulder 38 which is adapted to engage a downwardly turned lug 39 upon the brake lever 22 to retain the brake lever in the position indicated in Fig. 2 of the drawing. This latch also maintains the guide bar 27 and the feed screw 34 in parallel relation to enable the clutch member 30 to be advanced by the feed screw when the clutch sleeve 35 of the member 30 is in mesh with the threads upon this rod. 100

The feed screw 34 has its reduced inner 105 end supported by an upturned lug 40 formed on the inner extremity of the base plate 10. The outer extremity of this screw is supported by a bracket 41 which has its inner extremity 42 secured to the base plate by 110

the rivet forming the pivot 23. This bracket has an upturned portion 43 and a downturned end 44 through which the reduced outer extremity of the feed screw 34 passes.

5 The end portion 44 of the bracket abuts against the shoulder formed at the junction of the reduced end of the feed screw and the larger threaded portion to coat with the lug 40 to prevent longitudinal movement 10 of the screw. A toothed wheel or ratchet 45 is secured upon the inner end of the feed screw 34 and is adapted to be operated by a finger 46 of thin spring metal secured upon the under face of the turn-table 47 in 15 the manner indicated in Fig. 3 of the drawing. This finger is provided with an inclined face 48 which is disposed in the path of the teeth of the wheel 45 so that this face contacts with the tooth presented and provides a rotation of the wheel one tooth distance. The extremity 49 of this finger is turned upwardly so that when the inclined face of the finger yieldingly rides over the tooth the extremity of the finger engages 25 the next tooth and prevents any spinning of the wheel. The primary function of this type of finger is to eliminate noise due to the impact of the finger with the wheel which would be most likely to occur when 30 a stationary wheel is struck by a rapidly moving rigid member.

The trip 20 is adjusted by the index pointer 13 in order to cause the latch lever to be automatically released at the completion 35 of the rendition of the selection on the record. This trip is rotated upon the pivot 21 as a center by movement of the index pointer 13 relative to the graduated dial 12, but such movement of the index pointer 40 and the trip does not move the latch lever. Similarly the movement of the trip by the engagement of its free end with the clutch member 30 moves the latch lever but does not move the index pointer.

45 A manually operated auxiliary stop lever 51 is pivotally mounted upon the base plate 10 at 52. A link 53 connects the inner extremity 54 of the lever 51 with the latch lever 18. A thumb piece 55 is provided on 50 the outer extremity of this lever 51 to enable the brake lever 22 to be released at any time during the operation of the phonograph and thus stop the turn-table.

55 The clutch member 30 is moved into and out of operative engagement with the feed screw 34 by the clutch lever 22' which is pivotally connected to the brake lever 22 at 56. This lever 22' is provided with a short arcuate slot 57 through which passes 60 the eyelet forming the pivot 25. This eyelet is crimped upon the brake shoe 24 pivoted thereon and forms a frictional engagement between the arm 26 of the base plate, the clutch lever 22', and the brake. Movement 65 of the outer extremity 58 of the clutch lever

in a clockwise direction from the extreme position indicated in Fig. 1 first causes the lever to swing on its pivot 56, moving the clutch member 30 out of engagement with the feed screw. This movement is permitted by the slot 57. When the end of the slot is reached, further clockwise movement of the extremity 58 of the clutch lever causes this lever to turn on the pivot 25 as a center, swinging the brake lever upon the pivot 23 in a clockwise direction sufficiently to cause the latch lever to engage the locking lug on the brake lever, in the position indicated in Fig. 2 of the drawing. During this movement the brake shoe is moved out of engagement with the turn-table and the latter commences to rotate. When the brake lever is thus locked, movement of the extremity 58 of the lever 22' in a counter clockwise direction causes this lever to rotate on the pivot 56 and to throw the clutch member 30 into operative engagement with the feed screw.

In the operation of the device the index pointer is set at the proper graduation to position the trip so that the turn-table is automatically stopped upon the completion of the playing of the selection. Different records have different lengths of sound-reproducing grooves usually defined by the number of record lines between the axis of the record and the periphery thereof. The advance of the thread on the feed screw 34, the number of teeth upon the feed wheel or ratchet, and the graduation of the dial, are so related that the extreme positions of the indicating pointer shall locate the trip to stop the motor at the proper time for the maximum and minimum number of lines found on any records. The average record requires a setting at the graduation 10.

Having moved the clutch member 30 out of operative engagement and started the rotation of the turn-table in the manner described, the stylus should now be placed in the record groove. As soon as the rendition of the selection begins, the clutch lever 22' should be thrown to the right to engage the clutch member and start the advance of this member on the feed screw. The trip having been properly positioned for the particular record on the turn-table, will be engaged by the clutch member at the completion of the selection, and the brake lever released, automatically setting the brake and stopping the rotation of the turn-table. When the brake lever is released, the clutch member is disengaged from the feed screw and is moved to its initial position by the spring 31.

The turn-table may be manually stopped at any time during the playing of the selection by the auxiliary stop lever 51.

The proper setting of the index pointer for any particular record is determined by

setting the pointer at the graduation 0, starting the playing in the usual manner, and then manually stopping the turn-table at the completion of the playing of the selection, or 5 as soon thereafter as is desired, by grasping it with the hand. The index pointer is now slowly moved to the right until the trip strikes the clutch member and sets the brake. The position of the pointer on the dial at the 10 time of actuation of the stop mechanism should be noted and the number of the graduation marked upon the record. In all playing of this record thereafter, the pointer should be set at the graduation thus determined and the record will be uniformly stopped at the proper point.

It will be readily evident that with the present invention, the operation of the phonograph may be automatically and accurately stopped at the completion of the rendition of the selection on records of any length. Also the operation may be stopped by auxiliary stopping means independently of the automatic action at any time. The 25 device operates noiselessly and without interference with the running of the phonograph. The mechanism with the exception of the control levers, the dial, and the index pointer, is entirely concealed beneath the turn-table. The device may be readily attached to any phonograph and located in the most convenient position about the axis of the turn-table. No parts of the stop mechanism are carried by or attached to 30 the tone arm. This eliminates the necessity for drilling holes in the tone arm, the unattractive appearance of parts of this nature when so attached, and the constant danger of accidental displacement of these parts. 35

40 I am aware that a considerable number of changes may be made in the construction and arrangement of parts without departing from the spirit of my invention, and I reserve the right to make all such as fairly fall within the scope of the following claims.

45 I claim:

1. In a phonograph, the combination with a revoluble turn-table, of an automatic stop mechanism for said turn-table, means revoluble with said turn-table for actuating said mechanism, and adjustable means movable independently of said mechanism to cause the same to stop said turn-table at the completion of a predetermined number of revolutions of said turn-table.

2. In a phonograph, the combination with a revoluble turn-table, of an adjusting member, automatic stop mechanism controlled by said member and movable independently thereof to stop said turn-table at the completion of a number of revolutions determined by the position of said member, and means revoluble with said turn-table for actuating said stop mechanism.

65 3. In a phonograph, the combination with

a revoluble turn-table, of an index pointer, a dial, automatic stop mechanism controlled by said pointer and movable independently thereof to stop said turn-table at the completion of a number of revolutions determined by the relative position of said pointer and dial, and means revoluble with said turn-table for actuating said stop mechanism.

4. In a phonograph, the combination with a revoluble turn-table, of automatic stop mechanism for said turn-table including a feed screw actuated by the rotation of said turn-table, a latch, a trip for said latch, and a trip actuating member fed by said screw.

5. In a phonograph, the combination with a revoluble turn-table, of automatic stop mechanism for said turn-table including a feed screw actuated by the rotation of said turn-table, a latch, a trip for said latch, a trip actuating member normally disengaged from said screw, and means for moving said member into operative engagement with said screw to cause said member to be advanced thereby to actuate said trip.

6. In a phonograph, the combination with a revoluble turn-table, of automatic stop mechanism for said turn-table including a feed screw actuated by the rotation of said turn-table, a brake, a brake lever, a latch for said brake lever, a trip for said latch, a trip actuating member, and a clutch for operatively engaging said member with said screw to cause said member to be moved toward said trip by said screw.

7. In a phonograph, the combination with a revoluble turn-table, of automatic stop mechanism for said turn-table including a feed screw intermittently actuated by the rotation of said turn-table, a latch, a trip for said latch, a trip actuating member, and a manually controlled clutch for operatively engaging said member with said screw.

8. In a phonograph, the combination with a revoluble turn-table, of automatic stop mechanism for said turn-table including a feed screw actuated by a projection on said turn-table, a latch, an adjustable trip for said latch, and means actuated by said feed screw for operating said trip.

9. An automatic stop mechanism for phonographs comprising a latch, a trip for said latch, feed screw, and means operated by said feed screw for actuating said trip to release said latch at the termination of a predetermined number of revolutions of said feed screw.

10. An automatic stop mechanism for phonographs comprising a brake, a brake lever, a latch for said lever, an adjustable trip for said latch, a feed screw, and a trip actuating member operable by said screw.

11. An automatic stop mechanism for phonographs comprising a brake, a brake lever, a latch for said lever, an adjustable trip for said latch, a feed screw, a trip actu-

ating member, and a clutch for operatively engaging said member with said screw.

12. An automatic stop mechanism for phonographs comprising a brake, a brake lever, a latch for said lever, a trip for said latch, a trip actuating member, a feed screw for advancing said member toward said trip, and means for adjusting the position of said trip.

13. An automatic stop mechanism for phonographs comprising a brake, a brake lever, a latch for said lever, a trip for said latch, a trip actuating member, a feed screw for advancing said member into operative engagement with said trip, and means for returning said member to its initial position upon the release of said latch by said trip.

14. In a phonograph, the combination with a revoluble turntable, of automatic stop mechanism for said turntable including 20 a feed screw actuated by a member revoluble with said turntable, a latch, an adjustable trip for said latch, and means actuated by said feed screw for operating said trip.

15. In a phonograph, the combination 25 with a revoluble turn table, of automatic stop mechanism for said turn table, a finger revoluble with said turn table for actuating said mechanism and means adjustable independently of said mechanism for tripping said mechanism to cause the same to stop said turn table at the completion of a predetermined number of revolutions.

MARIUS E. GRISWOLD.
